NURSING NIPPLE

Jesse Little, Warwick, R. I., assignor to Davol Rubber Company, a corporation of Rhode Island

Application April 25, 1945, Serial No. 590,234

3 Claims. (Cl. 128—252)

1

The present invention relates to nursing bottle arrangements, and has particular reference to a novel construction of a dual purpose feeding nipple suitable for use with medium mouth nursing bottles and with small mouth nursing and fruit and vegetable juice bottles.

It is the principal object of the invention to provide a novel nipple construction which provides a continually open air vent when used.

Another object of the invention is to provide a nipple construction which is self-seating when the retainer cap and the nipple are mounted on the nursing bottle.

A further object is to provide a nipple construction which can be interchangeably used with a medium mouth nursing bottle and with a small mouth bottle.

With the above and other objects and advantageous features in view, the invention consists of a novel arrangement of parts more fully described in the detailed description following, in conjunction with the accompanying drawings, and more specifically defined in the claims appended thereto.

In the drawings,

Fig. 1 is an elevation of an assembled nursing bottle, feeding nipple, and retainer cap, the nipple being constructed in accordance with the invention;

Fig. 2 is a vertical sectional detail of the upper portion of Fig. 1;

Fig. 3 is a view similar to Fig. 2, the nipple being in reversed position and the bottle sealed for carrying when travelling, or for storing in advance of use;

Fig. 4 is a top plan view of a suitable retainer cap;

Fig. 5 is a bottom plan view thereof;

Fig. 6 is a plan view of a sealing disk;

Fig. 7 is a vertical central sectional view thereof;

Fig. 8 is an elevation of the novel feeding nipple;

Fig. 9 is a top plan view thereof;

Fig. 10 is a bottom plan view thereof;

Fig. 11 is a central vertical section on the line 11—11 of Fig. 10;

Fig. 12 is a detail section on the line 12—12 of Fig. 11; and

Fig. 13 is a sectional detail showing the nipple mounted on a small mouth bottle.

The variety of feeding formulae provided for infants because of their age and nursing effects, and the increasing feeding of fruit and vegetable juices, have created a need for an im-

2

proved nipple which may be used for general feeding. To this end, I have devised a nipple construction which provides a continually open vent when used either with a medium mouth bottle or with a small mouth bottle.

Referring to the drawings, the novel nipple 10 is shown mounted on a medium mouth nursing bottle 11 by means of a threaded retainer cap 12. The nipple 10, which is of hollow type, has a feeding tip 13 of generally spherical shape which is provided with one or more feeding passages 14, three being the preferred number, a body portion 15 which has a rounded outer surface and is of generally greater diameter as illustrated, and an annular base flange 16 of generally circular form.

The outer surfaces of the feeding tip and the body portion gently merge together, and the inner wall of the upper section of the body portion 20 extends inwardly and downwardly to provide a depending flange 17 and a generally cylindrical feed channel 18 which communicates with the tip 13 and the passages 14, the resulting thickened area 19 at the upper end of the body portion providing a substantial but yielding resistance to the feeding pressure of the infant's mouth. The base flange 16, see Figs. 10 and 11, is provided with a flat lower surface 20 and a slightly dished or concave upper surface 21, thus forming a thickened rim portion 22; an air vent channel or groove 23 is formed in the lower flange surface, preferably extending radially inwardly from the flange rim for a substantial distance, and two raised bars or ribs 24 are provided extending on the sides of and in slightly spaced parallel relation to the channel 23.

The base flange has the usual central circular inlet opening 25, the edge being preferably bevelled as indicated at 26, and the lower section 40 of the body portion extends inwardly to form an annular bead 27 which is spaced above the lower surface of the base flange and forms an inner shoulder 28. The inner wall 29 of the body portion is preferably provided with one or more vertical ribs 30 which extend over the upper surface 31 and the inner wall 32 of the annular bead 27, as illustrated.

The cap 12 is preferably made of a suitable material such as molded phenol condensation products or the like, so that it may be readily sterilized, and has a flat top portion 33 provided with a central opening 34 and a depending internally threaded edge portion 35, the under surface 36 of the top portion tightly engaging the thick-ended rim portion 22 of the base flange when

mounting the nipple on a medium mouth nursing bottle. The under surface 36 may be provided with an annular bead (not shown), if desired, to increase the gripping effect. When the nipple is mounted on a medium mouth nursing bottle there is thus a continuous vent, the air entering through the threaded areas of the bottle and the cap and through the vent channel 23. Since the nipple is made of resilient rubber or of similar material, the two bars 24 serve to effectively prevent flattening of the vent channel when the retainer cap is tightened.

The nipple and cap parts are proportioned so that the width of the nipple base flange is slightly less than the inner diameter of the cap, and is slightly greater than the inner diameter of the cap threads. When it is desired to mount the nipple on a nursing bottle the sterilized nipple is dropped into the retainer cap and the threading pressure forces the rounded body portion walls, which are resilient, through the cap opening and seats the nipple base flange firmly against the lower surface of the cap, with the edge of the cap opening positioned between the rounded body portion walls and the base flange. The nipple is thus releasably retained within the cap.

The nipple may be readily reversed on the medium mouth bottle for travelling or for preparing the feeding formula in advance of feeding, as shown in Fig. 3. In this position a closure disk 37 of rubber or other suitable material having a flange 38 and an elevated circular boss 39 adapted to seat within the retainer cap opening 34, is preferably utilized as illustrated in Fig. 3, thereby the nipple is protected from contacting unsterile surfaces or objects, and also functions as a seal.

Although the novel nipple construction is particularly suitable for use with medium mouth nursing bottles, it is also adapted for use with standard type small mouth nursing bottles, and similar small bottles used for feeding orange juice, tomato juice, and the like, the nipple parts being arranged to facilitate the mounting and the removal of the nipple and to increase the feeding effectiveness. When mounting the nipple on a standard type bottle the neck of the bottle is inserted into the nipple opening past the bevelled edge to contact the inner shoulder 28 of the annular bead 27; a finger of one hand being pressed against the nipple at this point just above the base flange, the other hand readily grasps the opposite end of the flange and draws the nipple over the bottle rim 40 to mount the nipple as illustrated in Fig. 13. In this position the bottle rim seats within the inner wall 29 of the body portion, and the depending flange 17 depends into the bottle neck. The vertical rib 30 extends around the rim 40 and into contact with the bottle neck to provide narrow air vents at its sides, thus facilitating the feeding operation.

The novel nipple construction is thus a dual purpose device, suitable for use with either a medium mouth nursing bottle or a standard type small mouth bottle, and has special advantages in that it is readily mounted and removed, and in that a continuously open vent is provided which facilitates liquid flow and eliminates all danger of nipple collapse.

While I have described a specific constructional embodiment of nursing nipple, it is obvious that the size, the relative arrangement, and the pro-

portions of the nipple and the retainer cap parts may be changed to accord with different feeding requirements, without departing from the spirit and the scope of the invention as defined in the appended claims.

I claim:

1. A feeding nipple comprising a hollow body portion of generally cylindrical form having its upper walls extending inwardly and upwardly to provide a feeding tip having a feeding passage therethrough, and a base flange extending outwardly from the lower walls of the hollow body portion and having a circular rim adapted to seat on the neck of a feeding bottle, the lower surface of the base flange having a radial air vent channel extending inwardly from the rim and adapted to extend over the feeding bottle neck and a raised bar positioned adjacent the side of the air vent channel.
- 10 2. A feeding nipple comprising a hollow body portion of generally cylindrical form having its upper walls extending inwardly and upwardly to provide a feeding tip having a feeding passage therethrough, and a base flange extending outwardly from the lower walls of the hollow body portion and having a circular rim adapted to seat on the neck of a feeding bottle; the upper surface of the base flange tapering inwardly from the edge to the body portion to provide a thickened rim, the lower surface of the base flange having a radial air vent channel extending inwardly from the rim and adapted to extend over the feeding bottle neck and a raised bar positioned adjacent the side of the air vent channel.
- 15 3. In combination, a medium mouth nursing bottle having a neck, a nipple comprising a body portion terminating in a feeding tip having a feeding passage therethrough, and a base flange having a circular rim and extending laterally from the lower edge of the body portion, and a retainer cap adapted to be secured to the bottle neck with the nipple base flange mounted on the bottle rim, said nipple base flange having a radial air vent channel in the lower surface thereof extending from the flange rim inwardly to provide an open air vent across the rim of the bottle neck to the bottle interior when so mounted, said lower flange surface having a raised bar positioned adjacent the side of the radial air vent channel.
